United States Patent

Des. 234,584
Patented Mar. 25, 1975

234,584

SLED

George M. Morris, Independence, Mo., assignor to G. M. Morris Boat Co., Inc., El Dorado Springs, Mo.

Filed Oct. 12, 1973, Ser. No. 406,952

Term of patent 14 years

Int. Cl. D12—14

U.S. Cl. D12—6

Fig. 1.

Fig. 2.

Fig. 3.

Fig. 4.

Fig. 5.

FIG. 1 is a perspective view of a sled embodying my new design;

FIG. 2 is a top plan view of the sled;

FIG. 3 is a side elevational view of the sled;

FIG. 4 is a front elevational view of the sled; and

FIG. 5 is a rear elevational view of the sled.

In FIGS. 2-5 portions of the cord have been omitted for ease of illustration.

I claim:

The ornamental design for a sled, as shown and described.
